PRACTICE GOLF CLUB

Paul Ahles, St. Cloud, Minn.

Application June 5, 1934, Serial No. 729,135

4 Claims. (Cl. 273—77)

This invention relates to a unique golf club of the species generally referred to in the trade as a driver, wherein the same is expressly constructed to perform in the capacity of a practice club. It is a matter of common knowledge that various appliances, accessories and contraptions have been developed with the view toward aiding players and students of golf to improve their game by the development of a proper golf swing. The present invention relates to this general field of development and has particular reference to a club which is somewhat in the nature of an innovation and based on an entirely new principle and structure to accomplish the desired ends. Merely as a matter of convenience, this improved practice club is of the dummy type and possesses conventional shape and proportions, but includes a peculiarly constructed head fashioned to accommodate a standard golf ball permitting the latter to be used as a directional projectile for ball flight indicating purposes. Those familiar with the universally recommended free golf swing are conversant with the rudimentary and fundamental requirements of the so-called "snap-of-the-wrist" action. This is calculated to give the desired impact at the time of striking the ball on the tee to promote control of the flight of the ball and to attain other advantages such as distance, etc. It has been discovered that by adapting the golf club head as hereinafter described and releasably connecting a golf ball thereto, it is possible to detect, by the flight of the ball, whether the golf swing is accurate and if and when the so-called follow through motion and action is perfected. These features and results will become more readily apparent from the succeeding description and the accompanying drawing.

In the accompanying drawing, wherein like numerals are employed to designate like parts throughout the same:

Figure 1 is a fragmentary elevational view of a golf club constructed in accordance with the principles of the present inventive conception.

Figure 2 is a top plan view with portions broken away and shown in section to disclose the details effectively.

Figure 3 is a perspective view of the ball-retention latch.

In the drawing, the shank of the club head is denoted by the numeral 4 and the head itself is distinguished by the numeral 5. As before stated, in general appearance, these parts are conventional. Moreover, the customary handle or shaft (not shown) is attached to the shank. Basically,

it is my idea to cut out a portion of the head as at 6 to form what may be designated as a pocket or receptacle for the golf ball 7. Incidentally, this is merely a practice golf ball and, of course, recommended for use merely as a matter of convenience. In other words, it could be any sort of a projectile which would fly out into the air under centrifugal action as the club head is swung through the customary arc. The pocket 6 therefore embodies a substantially flat bottom 8 and an upstanding wall 9, the remainder of the pocket being shaped to accommodate the ball. The ball, under ordinary circumstances, rises slightly above the crown portion of the head. It might also be stated that the head here is obviously made somewhat larger than the regulation head but that the club as a whole, that is, including the ball and other appurtenances, is made so as it weighs substantially the same as the standard driver.

Various ways may be utilized for releasably holding the ball or projectile 7 in the pocket 6. In the instant showing, this is accomplished by using what may be designated as a latch 10. This is suitably proportioned and shaped and preferably finished as at 11 to conform to and bear against the ball 7 to hold it in the the pocket. The inner end thereof, as at 12, is flexed laterally and pivoted as at 13 in a recess 14. Then adjacent this pivot there is a stud 15 carried by the latch and a coiled spring 16 is attached to this and extends through a bore 17 and is connected with an adjusting bolt 18 and associated nut 19 confined in the depression 20. It is obvious that this allows for sensitivity of control and proper tensioning of the latch to produce the requisite frictional retention of the ball or projectile 7 in its pocket.

It is further evident that with this arrangement when the ball is in place and held therein by the latch 10 and when the club is swung in the usual way at an imaginary tee shot, the centrifugal action developed as the club is swung, will throw the ball 7 out from the pocket.

With the right kind of tension exerted upon the ball through the release latch and with a delayed wrist movement, the ball will be projected straight forward in the line of flight, whereas wrist movement applied too early in the downward swing of the club will project the ball at an angle to the line of intended flight, the angle depending upon the time and force of the wrist action at the wrong time. To project the ball truly in line with the intended line of flight it is necessary to apply the wrist snap movement at the time the club head passes the point where

the golf ball is placed in playing the regular game. In order to project the ball in the line of flight it is necessary to swing the club right, and a player with a wrong swing will automatically correct his swing.

The gist of the invention is of course not so much in the theory of operation but directed to the adaption and use of a dummy golf club of the driver type wherein the head is fashioned to 10 serve as a holder for a ball or equivalent projectile, this being releasably held in place and adapted to be thrown out by centrifugal force, the arrangement being such that the features are related to dispose the ball along the so-called 15 face or lay of the club and to have the pocket open at the front and on one end cause the ball to take a flight corresponding to the swing and wrist motion. Thus by constant practice, the user can not only detect errors but can improve the 20 swing by following the direction of flight of the ball.

It is thought that persons skilled in the art to which the invention relates will be able to obtain a clear understanding of the invention after considering the description in connection with the 25 drawing. Therefore, a more lengthy description is regarded as unnecessary.

Minor changes in shape, size, and rearrangement of details coming within the field of invention claimed may be resorted to in actual practice, 30 if desired.

I claim:

1. A golf practice club embodying a head having a ball-receptive pocket, and a spring pressed 35 latch for holding the ball in said pocket, said pocket being open along the front edge and at one end and otherwise fashioned to accommodate and securely hold the ball therein until it is forcibly flipped from the pocket by centrifugal 40 action during the swinging of the club.

2. A dummy golf club for golf practice work comprising a flexible shaft of conventional length and tapered form, said shaft being fashioned to provide a hand grip at the customary end, and a 45 laterally directed head attached to the opposite

end of said shaft, said head being of customary design in bottom plan view, the top portion of said head being recessed to form a ball holding pocket, said pocket being open along the front edge or face of the head and open at the outer 5 end of said head, a resilient latch pivoted to the frontal portion of said head and extending across and closing the front portion of said pocket, spring retaining means anchored in said head and attached to the pivoted end of said latch for maintaining the latch in a position to resiliently and releasably hold a golf ball in said pocket.

3. A practice golf club comprising a flexible tapered shaft of standardized dimension, a head attached to the outer end of the shaft in a conventional manner, said head being of regulation shape and proportions in vertical and circumferential dimensions, a predetermined portion of the top, front and one end of said head being cut away to define a ball receptive pocket, a standard 15 golf ball located in said pocket, and resilient frictional retaining means on said head for holding the ball in the pocket, said retaining means and ball possessing an aggregate weight equivalent to that portion of the material removed from 20 the head in forming said pocket, whereby to make the overall weight of the club, ball and retaining means equivalent to that of an unaltered or conventional golf club.

4. A dummy driver for golf practice purposes 30 comprising a flexible shaft of conventional shape and proportion, a head of customary design secured to the outer end of the shaft, said head being fashioned to accommodate and hold a conventional golf ball, resilient trip means on the 35 head for retaining the golf ball temporarily in place, said trip means serving to release the golf ball for flight in a predetermined direction and manner, the weight of said head being reduced proportionately to compensate for the addition of 40 the trip means and ball so as to render the complete assembly usable without materially adding weight beyond that of a conventional unaltered golf club.

PAUL AHLES.
